CLAIM

The ornamental design for a cooking ring, as shown and described.

DESCRIPTION

FIG. 1 is a top, front, right and left side isometric view of a cooking ring showing my new design;

FIG. 2 is a bottom, front, right and left side isometric view thereof;

FIG. 3 is a right side elevation view, the left side elevation being identical thereto;

FIG. 4 is a front side elevation view, the rear elevation being identical thereto;

FIG. 5 is a top plan view thereof;

FIG. 6 is a bottom plan view thereof;

FIG. 7 is a cross-sectional view taken along line 7-7 of FIG. 5; and,

FIG. 8 is a cross-sectional view taken along line 8-8 of FIG. 5.

1 Claim, 5 Drawing Sheets
